UNITED STATES PATENT OFFICE.

DENNIS E. HARTNETT, OF NEW YORK, N. Y.

MUTE FOR STRINGED INSTRUMENTS.

1,177,184.

Specification of Letters Patent. Patented Mar. 28, 1916.

Application filed July 25, 1913. Serial No. 781,058.

To all whom it may concern:

Be it known that I, DENNIS E. HARTNETT, of New York, in the county of New York and in the State of New York, have invented 5 a certain new and useful Improvement in Mutes for Stringed Instruments, and do hereby declare that the following is a full, clear, and exact description thereof.

My invention relates particularly to mutes 10 which are adapted to be applied to all plectrum and bowed instruments.

The object of my invention is to provide a 15 mute which is arranged so as to be capable of being thrown into and out of position without interruption in the playing of the instrument, and which is so constructed that it is at all times in a position in which it cannot interfere with the operation of the instrument. The construction is such further- 20 more that a new string can be readily inserted without removing the mute. Furthermore when adjusted to the rear of the bridge it does not diminish the tone.

A further object of my invention is to pro- 25 vide a mute which may be readily applied to instruments having bridges of different thicknesses, and which is so arranged that the volume of sound may be controlled from a point where an artistic effect is to be pro- 30 duced, to a point where it is desired to suppress practically all of the sound. This is a positive advantage as it facilitates acquiring the technique of notation in music, that is to say, learning how to play music, when 35 used with the developer covered by my Patent No. 1,047,217, granted December 17, 1912.

While my invention is capable of being embodied in many different types of apparatus, I have, for the purposes of illustration, shown only one form of my invention 40 in the accompanying drawings, in which—

Figure 1 is a plan view of an instrument equipped with a mute showing the mute in operative position; Fig. 2 is a smaller view of 45 the same showing the mute moved to its intermediate position when temporarily out of operation; Fig. 3 is a similar view showing the mute moved to a point over the lower ends of the strings, the position in which 50 the mute is not to be used during the playing of a selection; Fig. 4 is a side elevation enlarged of the lower portion of the instrument, showing the parts in the same position as in Fig. 2; Fig. 5 is a plan view enlarged 55 of the mute detached; Fig. 6 is a vertical section through the same on line 6—6' of Fig. 5;

and Fig. 7 is a plan view of a mute made in accordance with my invention and adapted to be used in connection with bowed instruments. 60

In the drawings, I have shown a mandolin 1 having a bridge 2 and a series of strings 3. The lower ends of the strings 3 are protected by means of a casing or cover 4. To an instrument of this character I apply a mute 5 made in accordance with my invention. 65 This mute 5 comprises a body 6 made preferably of a single piece of sheet metal. This is bent in a form so as to provide a transverse upper plate 7 and two sides 8. Each 70 of the sides 8 has a rear tapered portion 9 having a plurality of notches 10 for receiving a shaft 11 of a rubber roller 12. The side portions 6 at the front are reduced in width to produce narrow members 13 having notches 14 to receive an axle 15 of a rubber roller 16. At their lower edges the side portions 6 are also provided with hooks 17 to receive the axle 18 of a rubber roller 19. 75 It will be seen from Fig. 5 that the rollers 12, 16 and 19 are of different sizes, one being smaller than the other in the order named. By this means a great many different degrees of pressure may be obtained on the 80 strings by interchanging the positions of the 85 rollers, in the several positions provided in the mute for receiving the same. In fact, by interchanging the positions of the rollers twenty-seven different degrees of pressure 90 can be obtained. The rubber rollers 12, 16 and 19 are of different sizes so that different 95 degrees of pressure may be obtained by substituting one for another. Furthermore, the rear tapered members 9 having notches 10 provide a means for increasing the pressure 100 by moving the rubber roller 12 to one of the notches located nearer to the center of the mute. When the rubber roller is supported in the notches 10 located at the extreme rear of the device, artistic effects are obtained, 105 while with the movement of the roller to the notches located nearer to the center of the device, the sound is decreased in volume until it is practically suppressed. The normal 110 position of the mute is with the rollers 12 and 18 located at the rear of the bridge 2 and if the mute is in position to damp the vibrations of the strings, the other roller 16 is located over the vibratory portions of the strings in front of the bridge. When it is 115 desired to throw the mute out of its position it is merely necessary to move the same to

the rear of the instrument, and this can readily be accomplished without interfering with the playing of the selection. When so moved the bridge occupies a position with the roller 16 just in the rear of the bridge 2. 5 If it should be desired to dispense with the use of the mute altogether, it may be moved downwardly over the casing 4 or the lower ends of the strings. The mute can be moved 10 into and out of position on the instrument silently while playing. This is preferably done where rests occur in the music or at the end of phrases or strains.

The modification of my invention shown 15 in Fig. 7 is adapted for application to bowed instruments. This modification is constructed in the same manner as the mute shown in Fig. 5, except that a different form of roller is used. In this modification of 20 my invention, I make use of three separate roller devices 20, 21 and 22. Each of the roller devices is arranged to be interchangeable in the many different positions contained upon the mute 5, and I make the 25 three roller devices 20, 21 and 22 of three different sizes so that by interchanging the same in the three different positions upon the mute 5, I may obtain twenty-seven different degrees of pressure upon the strings. 30 Each of these roller devices comprises a bent rod 23 having flanges 24 upon its end to retain in place a plurality of separate and independent rollers 25. Each of the rollers 25, of which there are a sufficient number so 35 that one of the rollers may be applied to each of the strings upon the instrument, is loosely pivoted upon the rod 23 and has a concave periphery so as to be retained in place upon the string to which it is applied. 40 This modification of my invention operates in general in the same manner as the modification of my invention previously described, except that the mute when supplied with rollers of this kind is to be applied to 45 a bowed instrument instead of a plectrum instrument.

While I have described my invention above in detail, it is to be understood that many changes may be made therein without departing from the spirit of my invention. 50

I claim:

1. A damping device for plucked and bow instruments having strings, comprising an intermediate engaging roller and two end 55 engaging rollers to partially suppress the sound, wholly and movably supported by the strings and engaging the vibratory portions of the strings.
2. A damping device for stringed instruments, comprising two end engaging rollers, and an intermediate engaging roller wholly supported by the strings, the intermediate one below and the others above the strings, and engaging the vibratory portions of the 60 strings to partially suppress the sound.

3. A damping device for stringed instruments, comprising two end engaging rollers, and an intermediate engaging roller wholly supported by the strings, the intermediate one below and the others above the 75 strings, and engaging the vibratory portions of the strings to partially suppress the sound, all three rollers being of different sizes, and being located unequal distances from one another. 75

4. A damping device for plucked and bow instruments having strings, comprising an intermediate engaging roller and two end engaging rollers to partially suppress the sound, wholly and movably supported by 80 the strings and engaging the vibratory portions of the strings, one of the rollers being adjustable to adjust the distance of the intermediate roller to and from the planes of the other two rollers. 80

5. A damping device for stringed instruments, comprising two end engaging rollers, and an intermediate engaging roller wholly supported by the strings, the intermediate one below and the other above the strings, 90 and engaging the vibratory portions of the strings to partially suppress the sound, one of the rollers being adjustable to adjust the distance of the intermediate roller to and from the plane of the other two rollers. 95

6. A damping device for stringed instruments, comprising two end engaging rollers, and an intermediate engaging roller wholly supported by the strings, the intermediate one below and the others above the strings, 100 and engaging the vibratory portions of the strings to partially suppress the sound, all three rollers being of different sizes, and being located unequal distances from one another, one of the rollers being adjustable to 105 adjust the distance of the intermediate roller to and from the plane of the other two rollers.

7. A damping device for plucked and bow instruments comprising two end string engaging rollers and an intermediate string engaging roller all of which are located on 110 different parallel axes.

8. A damping device for plucked and bow instruments comprising two end engaging rollers and an intermediate engaging roller 115 all of which are located on different parallel axes, the intermediate roller having its axis located in a different plane from the plane of the axes of the two end rollers. 120

9. A damping device for plucked and bow instruments comprising two end engaging rollers and an intermediate engaging roller all of which are located on different parallel axes, the intermediate roller having its axis located in a different plane from the plane of the axes of the two end rollers, all 125 said rollers being of different sizes and located at unequal distances from one another.

10. A damping device for plucked and 130

bow instruments comprising two end engaging rollers and an intermediate engaging roller all of which are located on different parallel axes, means for the adjustment of 5 one of the rollers to adjust the distance of the axis of the intermediate roller to and from the plane of the axes of the other two rollers.

11. A damping device for plucked and 10 bow instruments comprising two end engaging rollers and an intermediate engaging roller all of which are located on different parallel axes, the intermediate roller having its axis located in a different plane from the 15 plane of the axes of the two end rollers, means for the adjustment of one of the rollers to adjust the distance of the axis of the intermediate roller to and from the plane of the axes of the other two rollers.

12. A damping device for plucked and 20 bow instruments comprising two end engaging rollers and an intermediate engaging roller all of which are located on different parallel axes, the intermediate roller having its axis located in a different plane from the 25 plane of the axes of the two end rollers, all said rollers being of different sizes and located at unequal distances from one another, means for the adjustment of one of the rollers to adjust the distance of the axis 30 of the intermediate roller to and from the plane of the axes of the other two rollers.

In testimony that I claim the foregoing I have hereunto set my hand.

DENNIS E. HARTNETT.
